(57) **CLAIM**

The ornamental design for a wall mounted construction debris catcher with beveled sides and a flat bottom as shown and described.

DESCRIPTION

FIG. 1 is a front perspective view of a wall mounted construction debris catcher with beveled sides and a flat bottom per this invention;

FIG. 2 is a front plan view of the wall mounted construction debris catcher from FIG. 1;

FIG. 3 is a rear plan view of the same wall mounted construction debris catcher, or opposite view from that shown in FIG. 2;

FIG. 4 is a right side plan view of the wall mounted construction debris catcher from FIG. 2;

FIG. 5 is a left side plan view of the same wall mounted construction debris catcher, or opposite view from that shown in FIG. 4;

FIG. 6 is a top plan view of the same wall mounted construction debris catcher from FIG. 2; and,

FIG. 7 is a bottom plan view of the same wall mounted construction debris catcher, or opposite view from that shown in FIG. 6.

1 Claim, 7 Drawing Sheets
